UNITED STATES PATENT OFFICE

LAWRENCE D. STRONG, OF MAYWOOD, ILLINOIS

MOTION-PICTURE CHANGE-OVER DEVICE

Application filed August 2, 1926. Serial No. 126,699.

In producing motion pictures, it is customary to provide two or more projecting machines, and at times these are used in combination with stereoscopic machines in order to produce moving pictures as well as still pictures. In the operation of these machines, it is desirable at times to change from one to another, as for instance when one reel of a film is finished in one machine, which is then cut out and another machine with the next reel is cut in without any appreciable delay or interruption. The present invention relates to systems for making such changes or changeovers and to means whereby these operations may be made in a convenient and satisfactory manner.

The objects of this invention are to provide an improved system of changeovers for projecting machines; to provide an improved changeover system whereby one projecting machine in a cooperating group such as picture machine, stereoscopic machine and effect machine may be cut in and all other projecting machines will be cut out, from any convenient point in the booth or projecting room; to provide an improved shutter mechanism for changing a picture from one machine to another; to provide a device of this character which may be readily installed in the wall of the projecting room or which may be attached to the machine; and to provide such other advantages and novel features as will be described hereinafter.

In the accompanying drawings illustrating this invention:

Figure 1 is a side view of a projecting machine showing my improved changeover device attached thereto;

Figure 1^a illustrates the front wall of the projection booth with the change-over shown in dotted lines secured thereto;

Figure 2 is a diagrammatic view illustrating the method of wiring for two shutters or changeovers;

Figure 3 is a front view of the changeover showing the shutters in open position, parts being broken away to show the interior construction;

Figure 4 is a detail showing the solenoid mounting; and

Figure 5 is a sectional view taken on the line 5—5 of Figure 4.

In these drawings various parts are shown diagrammatically. As shown in Figure 1, the projecting machine 6, which may be of any ordinary or preferred form, is provided with the usual upper magazine 7 and lower magazine 8. My improved changeover device 9 may be conveniently supported on the machine by means of arms or brackets 10 and 11 which are connected respectively with the upper and lower magazines in order to support the changeover in front of the projecting lens. In some instances as when the projecting machine is moved close to the front wall it may be desirable to mount the changeover on the front wall 12 of the booth, as shown in dotted lines in Figure 1, in which case the shutter opening is arranged in front of the projecting lens and in alignment with the port opening 13 in the wall.

As shown in Figures 3 to 5 inclusive, the changeover device comprises a plate or casing 14 having an opening 15 in the front wall of the same, which is placed in alignment with the projecting machine. The upper part of the plate or casing has a flanged cover 16 which also has a hole or opening in alignment with the hole 15. The opening 15 is controlled by suitable shutters for opening and closing the same, which shutters are actuated by an electro-magnetic device. In the present instance, I have shown shutters 17 and 18 which are pivoted at 19 and 20 to the plate 14 and their lower ends are connected by means of links 21 and 22 with a rod or projection 23 on the slidable armature 24 of the double solenoid 25. The opposite end of the slidable armature 24 is provided with a rod 26 which extends out through the casing 27 so that the shutters may be operated by hand by moving this rod in and out which will swing the shutters on their pivots. The solenoid comprises two coils 28 and 29 which are provided with connecting or lead-in wires 30 and 31 and a common return wire 32. These wires are preferably brought out at either end between two protecting washers, 49, 50 as will be seen from Figure 4. The solenoid is secured to the plate 14 by means of a cap 33.

and screws 33. An abutment wall 34 extends up from the plate 14 at one side of the solenoid and sealing wax or the like 35 is poured in between the abutment and the solenoid and serves to insulate and support the connecting wires. The lower portion of the casting 14 is also provided with a cover 36 for protecting the solenoid and adjacent parts. It will be readily seen that when current is supplied to the coil 27, the armature 24 will be raised and the shutters will be swung outwardly as shown in full lines in Figure 3. A stop 37 is provided for engagement by the arm or projection 23 to limit the opening movement of the shutters. This stop is preferably made of rubber or other suitable resilient material and is held by means of a screw 38. When the shutters are to be closed, current is supplied to the lower coil 28 which pulls the armature down and swings the shutters to closing position, as shown in the dotted lines in Figure 3.

While, as above set forth, any desired number of projectors may be equipped with these changeovers and may be wired so that they may be operated in any desired sequence, I have shown in Figure 2 a wiring diagram for a pair of these devices. The solenoids 25 and 25^a are connected by wires 31 and 31^a with a wire 39 which leads from one terminal 40 of any suitable source of electricity. The opposite terminal 41 is connected by means of a wire 42 with a switch 43 and the wire 29 from the coil 27 leads to the switch contact 44. The wire 29 is also directly connected with the wire 30^a of the coil 28.

The wire 42 is also connected by means of wire 45 to the second switch 46. The contact 47 of this switch is connected by a wire 48 with the wire 30 of the coil 28 and with the wire 29^a of the coil 27.

When the switch 43 is closed and the switch 46 is open, as shown in Figure 2, the coils 27 and 28^a will be energized thereby opening the shutters operated by the first solenoid and closing the shutters of the second solenoid. When it is desired to change over, the switch 43 is opened and the switch 46 is closed. This will energize the coils 28 and 27^a thereby closing the shutters associated with the solenoid 25 and opening the shutters associated with the solenoid 25^a. The circuits are so simple that they will be readily understood by anyone familiar with this art and furnish an illustration of the connecting up of these devices for different conditions.

From this description, it will be seen that I provide changeover devices and a system of operation whereby the devices may be readily applied to any type of projecting machine and more particularly are entirely independent in operation from the machines. Furthermore, it will be apparent that changes may be made in the details of construction and arrangement of the parts without departing

from the scope of this invention, and therefore I do not wish to be limited to the particular features of construction herein shown and described, except as pointed out in the following claims, in which—

I claim:

1. The combination with a plurality of changeovers for a like number of moving picture machines, each changeover being operatively independent of the machine and each comprising a shutter and an electro-magnetic device having a plurality of windings for operating the same, each of said changeovers being positioned between its respective moving picture machine and the screen, a source of electricity and means for connecting the source of electricity with the respective windings whereby when any one shutter is opened the other shutters will be closed.

2. The combination with a pair of moving picture machines, of a pair of changeovers for a like number of moving picture machines, each changeover being operatively independent of the machine and each changeover being positioned in front of its respective machine and adjacent thereto, and comprising a shutter, a solenoid for operating each shutter, said solenoids having sectional windings and having movable armatures connected with the shutters, and a source of electric supply and conductors and switches for connecting the source of current with different windings on the respective solenoids whereby when one shutter is opened the other shutter will be closed.

3. The combination with a plurality of projecting machines, of electrically operated means for cutting off light from each machine, said means being placed between the projecting machines and the screen and being entirely independent in construction and operation from the projecting machine, circuits from a source of electricity to said means, and switches arranged in said circuits so that when any one of said means is opened all of the others will be closed.

LAWRENCE D. STRONG.
